ICE MAKING APPARATUS

James K. Nelson, Grove City, Ohio, assignor to Westinghouse Electric Corporation, East Pittsburgh, Pa., a corporation of Pennsylvania

Filed June 5, 1957, Ser. No. 663,711

14 Claims. (Cl. 62—135)

This invention relates to ice making apparatus, and more particularly to automatic ice makers of the type associated with domestic refrigerators for the production of ice pieces for household use.

This invention provides an improved power unit for ice makers of the type wherein water is frozen in a mold and frozen contents of the mold are removed or ejected by mechanical means. The invention is particularly applicable to flexible mold type ice makers such as are described and claimed in my copending application Serial No. 566,582 filed February 20, 1956, and entitled "Ice Maker," and in an application of Meigs W. Newberry, Serial No. 660,856, filed May 22, 1957, and entitled "Ice Maker," both assigned to the same assignee as this invention.

This invention contemplates the utilization of a thermal motor in producing forces for actuation of the ice making and removing mechanism. The thermal motor preferably takes the form of a confined substance capable of undergoing substantial volumetric changes when subjected to a change in temperature and wherein this change in volume is utilized to actuate a movable member, such as a plunger. Movement of this member is transmitted to the ice mold portion of the apparatus by unique and novel motion transmitting mechanisms which are herein-after described in greater detail.

In accordance with this invention, the thermal motor is so constructed as to function as a temperature-sensitive controller for governing its own actions. Heat is applied to the thermal motor to produce powered motion of its movable member for the purpose of performing the work of removing ice from the mold portion of the ice maker. A quantity of heat is stored in the thermal motor during this period which is subsequently removed by the same refrigerating means employed to cool and congeal the contents of the ice mold. The thermal system of the thermal motor is analogous to the thermal system of the ice mold and its contents and, inasmuch as they are subjected to the same refrigerating effect, the rates at which they are cooled are analogous, and the temperature of the thermal motor is analogous to the condition of the contents of the ice mold. The temperature of the thermal motor is reflected by the position of the movable member associated therewith and, by providing means for sensing the position of this member, certain appropriate bases are established for control of the ice making apparatus. Using these bases for control, the thermal motor is energized and deenergized at appropriate intervals to repetitively remove the frozen contents of the ice mold and refill the mold following completion of each ice freezing operation of the apparatus.

In many respects, the thermal motor is employed in this invention as an analog control of the type disclosed and claimed in my copending application, Serial No. 643,193 filed February 28, 1957, entitled "Ice Maker Control," and this invention is an improvement over the invention disclosed in that application.

2

Other novel features, objects and advantages of the invention will appear in the following detailed description, of which the accompanying drawings form a part and wherein:

5 Fig. 1 is a vertical sectional view through the freezing unit of a domestic refrigerator embodying an ice maker constructed in accordance with this invention;

Fig. 2 is an enlarged plan view of the ice maker shown in Fig. 1 but with the cover of the power mechanism 10 removed to show the interior thereof;

Fig. 3 is a fragmentary sectional view of the mold portion of the ice maker illustrating the manner in which ice is freed from the mold;

Fig. 4 is a sectional view through the ice mold taken generally as indicated by the line IV—IV in Fig. 3 and illustrating the manner in which ice is removed from the mold;

Fig. 5 is a fragmentary perspective view of the ice maker power mechanism with portions broken away to 20 show the construction of the thermal motor employed therein;

Fig. 6 is a schematic illustration of the power train shown in Fig. 5;

Fig. 7 is an electrical and water circuit diagram for 25 the ice maker and in which portions of the ice maker are illustrated schematically;

Fig. 8 is a diagrammatic illustration of the cycle of operation of the ice maker illustrated in Figs. 1 through 7;

Fig. 9 is a plan view of another ice maker embodying 30 a modification of this invention;

Fig. 10 is an enlarged front elevational view of the ice mold portion of the ice maker shown in Fig. 9 and illustrates the manner in which ice is removed from this mold;

Fig. 11 is a perspective view of the ice maker shown 35 in Fig. 9 with portions broken away to illustrate the construction of the power mechanism including the thermal motor;

Fig. 12 is a detailed illustration of a one-way clutch employed in the power train illustrated in Fig. 11; and

40 Fig. 13 is an electrical and water circuit diagram for the ice maker shown in Figs. 9 through 12, and wherein certain elements of the ice maker are illustrated schematically.

General arrangement

The general arrangement of a domestic type ice maker embodying this invention is illustrated in Figs. 1 and 2 in which the numeral 15 indicates, generally, an insulated refrigerator cabinet having a door 16 closing the front thereof. Only the upper portion of the cabinet 15 is illustrated and, as in many conventional domestic refrigerators, this portion of the cabinet contains a refrigerating unit 17 defining a freezer chamber 18. The refrigerating unit 17 includes a plurality of conduits 19 through which refrigerant is circulated to maintain a temperature within the freezer chamber 18 below the freezing point of water and generally at about 0° F. The refrigerating unit 17 is open at its front side to permit access to the freezing chamber 18 and a door 21 is provided for closing this access opening.

The automatic ice maker is disposed within the freezing chamber 18 and consists of several major components, including: An ice making and harvesting mechanism 22; a power mechanism 23 for driving the ice making and harvesting mechanism; a storage container 24 for receiving and storing the manufactured ice pieces; and a water filling system, of which only a filling tube 26 is shown in Figs. 1 and 2.

Ice making and harvesting mechanism

The ice making and harvesting mechanism 22 illustrat-

ed in Figs. 1 through 4 is of the type invented by Meigs W. Newberry and described more fully and claimed in his aforementioned patent application, Serial No. 660,856, filed May 22, 1957. This mechanism 22 includes a mold 27 made up of a plurality of serially connected arcuate pockets 28 adapted to receive water to be congealed into ice. The mold pockets 28 are refrigerated by a serpentine extension of the refrigerant conduit 19 which is bonded to center line portions of the bottoms of the mold pockets. The pockets 28 are constructed of a resilient material having good heat conducting properties, such as for example, beryllium copper, and are suspended from the upper wall of the refrigerating unit 17 by a resilient U-shaped bracket 29 which permits the mold 27 to be longitudinally stretched or lengthened to spread apart or distend the walls of each mold pocket 28 for the purpose of freeing ice pieces frozen therein. Mounted above the mold 27, and likewise supported by the bracket 29, is an ice removing device comprising a plurality of fingers 32 secured to a rotatable shaft 33 journaled in the bracket 29. The shaft 33 is preferably mounted directly above the longitudinal center line of the mold 27 and the fingers 32 are fixed at spaced intervals thereon in positions which permit each finger 32 to be swept through a mold pocket 28 when the shaft 33 is rotated. The shaft 33 also carries, for rotation therewith, a mold distending cam 34 positioned to cooperate with a bearing button 35 fixed to the mold support bracket 29 in a manner to effect a longitudinal stretching of the mold 27 each time the shaft 33 is moved through one complete revolution.

These elements of the ice making and harvesting mechanisms are arranged so that, when the shaft 33 is rotated through one revolution (counterclockwise as viewed from the front, see Fig. 4) from and back to the position shown in Figs. 1 and 2, the cam 34 longitudinally stretches the mold 27 in a manner to open up the walls of the mold pockets 28 to free the ice pieces therefrom, (see Fig. 3), the fingers 32 thereafter sweep through the mold pockets 28 to push the freed ice pieces out of the pockets and permit them to fall by gravity into the storage container 24, and the mold 27 is thereafter returned to its shortened condition.

Power mechanism

The shaft 33 of the ice making and harvesting mechanism is driven by the power mechanism 23, shown most clearly in Figs. 2, 5 and 6. The power mechanism 23 is preferably enclosed in a housing 41 positioned at the rear of the ice making and harvesting mechanism and rigidly mounted to the rear leg of supporting bracket 29 and the rear wall of the refrigerating unit 17.

Power for actuating the ice making and harvesting mechanism is derived from a thermal, or heat, motor, designated generally by the numeral 42, and disposed within the housing 41. In its preferred form, as shown in Fig. 5, the thermal motor 42 comprises a sealed container 43 enclosing an expansible-contractible material or substance 44 capable of undergoing a substantial volumetric change, usually accompanied by a change of state, when subjected to a change in temperature. Substances of this nature are referred to as being "morphologically transformable." In this instance a substance, such as a combination of paradichlorobenzene and cyclohexane which will undergo a volumetric change within the temperature range of 20° F. to 45° F., is employed. The container 43 has an opening in one end wall thereof which is sealed by a blind sleeve 46 made of flexible material, such as rubber or vinyl plastic. The sleeve 46 receives a tapered plunger 47 which projects through the opening in the container 43 and is connected to a slide member 48 carried in the bore of a sleeve bearing 49. The sleeve bearing 49 and the container 43 are supported by a wall 51 constructed of heat insulating material

and are rigidly held in place thereon by suitable fastening means. Disposed within the container 43 in intimate heat exchange relationship with the expansible-contractible material 44 is an electric heating element 52 supplied with electric current by conductors 53. In some instances, it is also desirable that the thermal motor include a thermal storage mass which may take the form of a cylinder of metal encompassing the container 43 as indicated at 54. For reasons which will become apparent hereinafter, that portion of the housing 41 which contains the thermal motor 42 is preferably lined or covered with a heat insulating material as indicated at 56.

The thermal motor 42 is energized by the electric heating element 52 which raises the temperature of the expansible-contractible material 44, causing it to expand and exert a constricting pressure or force around the flexible sleeve 46. When thus squeezed, the sleeve 46 urges the tapered plunger 47 out its open end with considerable force that the plunger transmits to the slide 48. When the heater 52 is deenergized and the temperature of the expansible-contractible material 44 is reduced by virtue of the thermal motor 42 being refrigerated by a pass of the refrigerant conduit 19 arranged in heat exchange relationship with the lower surface of the housing 41 (see Fig. 1), the material 44 contracts and the plunger 47 is moved back into the sleeve 46 as the sleeve is permitted to expand. The thermal motor 42 is constructed to force its plunger 47 to a fully extended position when the temperature of the motor reaches an upper predetermined value or limit of approximately 45° F., and to fully retract its plunger when its temperature is lowered to a lower predetermined value or limit of the order of 20° F. Thermal motors constructed in the manner described above are capable of producing forces of the order of 400 pounds over approximately a half inch range of movement of the plunger 47.

This forceful, limited movement of the plunger 47, is transferred into forces and movements capable of actuating the ice making and harvesting mechanism 22 by means of a power train positioned within the power mechanism housing 41. Referring to Figs. 2 and 5, the slide 48 carries a roller 57 which engages one edge of an oscillating beam 58 supported for pivotal movement about its lower end by a shaft 59. The opposite edge of the beam 58 is adapted to engage a roller 61 on a crankshaft 62 mounted for rotating movement (clockwise as viewed in Fig. 5) within the housing 41 about an axis disposed above and substantially parallel to the pivotal axis of the beam supporting shaft 59. This power train employs the oscillating beam 58 as a third class lever to transform the short reciprocating movements of the slider 48 into more pronounced rotary movements of the crankshaft 62. The crankshaft 62 is biased through its dead center positions with respect to the oscillating beam 58 by means of a tension spring 63 having one end thereof secured to the throw portion of the crankshaft and the other end thereof to a stationary support 60 on the far end wall of the housing 41 (Fig. 2).

Fig. 6 illustrates schematically the dead center positions of the linkage and the positioning of the spring 63 which enables it to pull the crankshaft 62 through these positions. As is believed to be apparent from this diagram, in order for the spring 63 to be effective in biasing the crank 62 through both of its dead center positions (indicated at A and B), the point of securement 60 of the stationary end of the spring 63 must be located somewhere within the acute angle α between planes C and D, passing through the pivotal axis of the crank 62 and, respectively, through the longitudinal axis of the crank arm in its two dead center positions with respect to the beam 58.

In addition to preventing the crankshaft 62 from becoming locked on dead center with the beam 58, the spring 63 also assists in returning the thermal motor

plunger 47 to the interior of sleeve 46 by pulling the beam 58 through the return portion of its movement.

The crankshaft 62 carries a cam 66 for actuation of an electric switch 67 mounted within the power mechanism casing 41. The forward end of the crankshaft 62 is coupled directly to the shaft 33 of the ice making and harvesting mechanism for driving the fingers 32 and the mold-distending cam 34.

Electrical and water-systems

As illustrated in Fig. 7, the switch 67 controls energization of the thermal motor 42 and a solenoid-actuated three-way water valve 71. The electrical circuit includes a source of electrical current indicated at L₁ and L₂ and a manually actuated on-off switch 72 by means of which the ice maker can be turned off. When switch 67 is closed, the heating element 52 of the thermal motor 42 is energized through the leads 53 and the solenoid valve 71 is also energized. When switch 67 is open, the heating element for the motor 42 is deenergized and the valve 71 is deenergized.

Water is conveyed to the automatic ice maker from a supply conduit 70 to the valve 71 which, when energized, connects the supply conduit to a water measuring chamber 73 having a flexible wall 74 capable of being flexed outwardly against the action of a spring load plunger 76 by the pressure of water entering the chamber 73. When valve 71 is deenergized, it connects chamber 73 with the mold filling conduit 26, and the measured quantity of water in chamber 73 is forced therefrom by the plunger 76, flows through filling conduit 26, and into the mold 27.

Referring to Figs. 5, 6 and 7, the switch actuating cam 66 is so constructed and mounted on the crankshaft 62 as to close switch 67 just as the slider 48 reaches its most retracted position, as produced by cooling of the expandable and contractible material 44 within the thermal motor 42. This position of the power train mechanism coincides with a dead center position A of the crankshaft 62-beam 58 combination and, in this position, the spring 63 rapidly moves the crankshaft 62 through its dead center position and effects abrupt, positive actuation of the switch 67 to its closed position. The elements of the ice making and removing mechanism are so constructed and arranged that, as the switch 67 is closed by the cam 66, the rise portion of the cam 34 is about to engage the pressure button 35 whereby continued rotation of the crankshaft 62 and shaft 33 will cause an elongation of the mold 27. The fingers 32 are arranged on the shaft 33 in such a manner that they effectively lag the rise portion of cam 34 by 90°, i.e., the fingers 32 are positioned to be brought into engagement with the ice pieces in the ice mold 27 by a further 90° rotative movement of the shaft 33 after the switch 67 is closed and the rise portion of the cam 34 encounters the pressure button 35. This relationship enables the full power available from the power mechanism 23 to be devoted to spreading the walls of the mold pockets 28 for the purpose of loosening the ice before the fingers 32 are swept through the pockets 28 to remove the ice.

The cam 66 is further constructed and arranged to open switch 67 when the sleeve 48 nears its most extended position as produced by heating of the thermal motor 42. This is the dead center position B for the crankshaft 62-beam 58 combination and again the spring 63 rapidly moves the crank 62 through this position to produce positive actuation of the switch 67. The switch 67 is opened as the ice removing fingers 32 are moved through and beyond the ice pockets 28 and the rise portion of cam 34 is moved out of engagement with the pressure button 35 to permit the mold 27 to return to a shortened condition preparatory to receiving a fresh supply of water.

6 Operation

Assume the mold pockets 28 of the ice maker are filled with ice which has just become frozen; in other words, the refrigerant conduit 19 has cooled the mold 27 to a temperature below freezing. In accordance with this invention, the power mechanism 23 will, at this time, also have been refrigerated to the predetermined temperature (approximately 20° F.) at which the thermal motor 42 has moved the power train to the position in which switch 67 is closed by the cam 66.

The closing of switch 67 initiates an ice removing operation of the ice maker which commences with the energization of the thermal motor heater 52. The solenoid valve 71 is simultaneously energized to admit water to the measuring chamber 73. As the expandable-contractible material 44 in the thermal motor 42 is heated it expands, moving the plunger 47 and the slide 48 to cause rotation of the crankshaft 62. As the crankshaft 62 and shaft 33 are rotated, the mold 27 is distended by the cam 34 and the ice pieces are loosened from their respective mold pockets 28 as the walls of these pockets are spread apart (see Fig. 3). Continued rotation of the shaft 33 under action of the thermal motor 42 swings the ice removal fingers 32 through the mold pockets 28, sweeping the ice pieces therefrom. The heat motor 42 continues to cause rotation of the crankshaft 62 until the cam 66 actuates switch 67 to its off position, deenergizing the thermal motor heater 52 and the solenoid valve 71. A measured quantity of fresh water then flows from the measuring chamber 73 to the filling conduit 26 and into the pockets of the ice mold 27.

The refrigerant flowing through conduit 19 extracts heat from the mold 27 and the freezing of ice in the mold pockets commences. This same refrigerating means also extracts heat from the thermal motor 42 by virtue of its contact with the bottom wall of the power mechanism housing 41. The thermal system of the thermal motor 42, including the heat storage mass 54, possesses a certain quantity of both latent and specific heat imparted thereto by the electrical heater 52. The insulating jacket 56 surrounding the thermal motor 42 is so designed that the rate at which this heat is extracted from the thermal motor 42 is analogous to the rate at which heat is extracted from the ice mold 27. Since the ice mold 27 and the thermal motor 42 are subjected to substantially the same refrigerating effect from the refrigerant conduit 19, the thermal motor 42 will have its temperature reduced to a predetermined value in the same period of time required to freeze the contents of the mold 27, regardless of changes in the refrigerating effect available from the refrigerant conduit 19. This predetermined temperature value is made to coincide with the temperature of the thermal motor at which the plunger 47 and slide 48 assume their most retracted positions. This temperature value of the thermal motor 42 is preferably of the order of 20° F.

The upper and lower limits of temperature between which the thermal motor 42 is cycled, and which may be 45° F. and 20° F., respectively, need not coincide with the upper and lower temperature values between which the ice mold 27 cycles, the latter being of the order of 55° and 30° F., respectively.

The thickness and conductivity of the insulation 56 surrounding the thermal motor 42 is preferably chosen such that the thermal motor 42 will be cooled to the temperature at which switch 67 is closed in a slightly greater period of time than is normally required to freeze ice in the mold 27. This excess time allows a safety factor to compensate for variables affecting freezing time, such as variations in the temperature of the water admitted to the ice mold 27.

During the period ice is being formed in the mold 27 and the thermal motor 42 is cooling, the ice removal fingers 32 are rotated in the free space above the ice mold 27 and their movement in no way interferes with

the freezing of ice in the mold. The cam 34 is also rotated during this period and is provided with a dwell area which does not move the mold 27 (see Fig. 8).

Modified ice making and removing mechanism

Figs. 9 through 13 illustrate a modified power mechanism constructed in accordance with this invention and applied to a different type of ice making and removing mechanism. Elements common to this apparatus and the previously described embodiment are identified by like reference numerals. In this apparatus, ice is formed in a trough-like flexible mold 81 supported for movement toward and away from a heat conducting support 82 mounted on the side wall of a refrigerating unit 83. The mold 81 is carried by front and rear pivot plates, indicated respectively at 84 and 85, which are independently, pivotally attached to the supported 82.

The plates 84 and 85 support the mold 81 for swinging movement about one longitudinal edge of the mold and the front plate 84 carries a stop pin 86 engageable with the support 82 for limiting movement of the forward end of the mold 81. The rear pivot plate 85 is rotatable by a shaft 87 through an angle greater than the forward pivot plate 84 is permitted to turn for the purpose of lifting the mold 81 from its support 82 and imparting to the mold a twist when it is partially inverted to loosen and eject ice therefrom. The action of the mold 81 in releasing ice is illustrated in Fig. 10. Ice pieces leaving the mold 81 fall into a removable storage tray, indicated at 88, in Fig. 9. The mold 81 is filled with water by means of a fill conduit 26 when it is in an upright position and resting on the support 82. This ice making and removing mechanism is described more fully and claimed in my previously-mentioned copending application, Serial No. 566,582 filed February 20, 1956.

Modified power mechanism

An oscillating motion is intermittently imparted to the drive shaft 87 of the ice making and removing mechanism by means of a power mechanism 91 disposed within a housing 92 disposed rearwardly of the ice mold 81 and mounted in good heat-exchange relationship with the refrigerating unit 83. As shown most clearly in Fig. 11 the power mechanism 91 employs a thermal motor 42 identical to the thermal motor previously described with reference to the first embodiment of the invention. In this modified power mechanism, however, the thermal motor plunger 47 is connected to a slider 93 having a gear rack 94 on its under surface. Reciprocating movement of the rack 94, as produced by the thermal motor 42 is transmitted to a pinion 96 connected, by means of a one-way clutch 97 (see Fig. 12), to a shaft 98 journaled in the housing 92. The clutch 97 is so constructed as to transmit only clockwise rotative movement (as viewed in Figs. 11 and 12) to the shaft 98. Consequently, only the power movement of the slider 93, as caused by energization of the thermal motor 42, is transferred to the shaft 98, and movement of the slider 93 produced by cooling of the thermal motor 42 produces no rotation of the shaft 98.

Intermittent unidirectional rotation of the shaft 98 is transmitted by a large gear 99 thereon to a smaller gear 101 for rotation, at an increased speed, of a shaft 102 carried in bearing supports 103 on the wall of the housing 92. Rotative movement of the shaft 102 is transmitted by a crank 104 on the end of the shaft to a slotted oscillating beam 106 by a crank pin 107 riding in the slot of beam 106. The slotted beam 106 is affixed to one end of the power shaft 87 and its oscillating motion is transmitted therethrough to the end of the mold 81.

The gear and lever elements of the power mechanism 91 are so proportioned as to move the mold support plate 85 from a substantially horizontal position in which the mold 81 rests on support 82 to the tray-twisted

position illustrated in Fig. 10 and back to a horizontal position each time the slider 93 is moved from its fully retracted position to its fully extended position by the thermal motor 42. These movements take place during the ice removing operation of this modified ice making apparatus.

Electrical and water systems

As in the previously described embodiment of the invention, energization of the heat motor 42 and a solenoid valve 71 is controlled by a switch 67 actuated by means which are connected to, and reflect the position of, the slider 93. The position of the slider 93 is, in turn, determined by the temperature of the thermal motor 42. The circuit for these elements is shown in Fig. 13. The switch 67 is mounted in a position to be actuated by a pair of upstanding lugs 108 and 109 on the slider 93. The arrangement is such that slider lug 108 opens switch 67 as the slider 93 nears the end of its range of movement when being propelled outwardly by the thermal motor 42. The slider lug 109 actuates switch 67 to closed position when the slider 93 nears the end of its range of reverse movement as occasioned by cooling of the thermal motor 42.

When closed, switch 67 connects supply lines L₁ and L₂ to the heating element of the thermal motor 42, initiating powered operation of the thermal motor, and also energizes the solenoid valve 71 to admit water from the supply conduit 70 into water measuring chamber 73. When opened, switch 67 effects deenergization of the thermal motor heater 52 and deenergization of the solenoid valve 71 permitting water to flow from the measuring chamber 73, through filling conduit 26, into the mold 81.

Operation of modified ice maker of Figs. 9-13

Completion of the freezing operation of the contents of the mold 81 is accompanied by cooling of the thermal motor 42 to a temperature which causes the slider 93 to move its lug 109 to a position to close switch 67. Energization of the thermal motor 42 by the switch 67 causes the expansible-contractible material 44 in the thermal motor 42 to expand and force the plunger 47 and slider 93 outwardly, away from the motor 42. Movement of the slider 93 is transferred through rack 94 and pinion 96 to shaft 98, through gear train 99, 101 and shaft 102 to crank 104 which oscillates beam 106 and mold pivot plate 85 to lift the mold 81 away from support 82, twist the mold 81 to remove ice therefrom, and return the mold 81 to its support 82. As the slider 93 nears the end of its outward movement, the lug 108 comes in contact with and opens switch 67. The thermal motor heater 52 is deenergized and the solenoid valve 71 is deenergized admitting water to the mold 81.

The thermal system of the thermal motor 42, as in the previously described embodiment, is analogous to the thermal system of the ice mold 81 and its contents, such that the time required to cool the thermal motor 42 to a temperature where the switch 67 is again closed is the same as, or slightly greater than, the time required to completely freeze the contents of the mold 81. The ice maker will automatically repeat the ice removing operation unless the line switch 72 is manually opened.

From the foregoing, it will be apparent this invention provides an improved power mechanism or drive arrangement for automatic ice makers wherein a thermal motor is employed both as a source of motive power and as a controller for itself and other elements of the ice making apparatus. While a thermal motor employing a confined, expandable-contractible substance is herein described, and is preferred for this application, it is to be understood that other thermo-motive devices, such as for example, thermo-sensitive bimetallic members, can be employed in practicing this invention.

While the invention has been shown in several forms,

it will be obvious to those skilled in the art that it is not so limited, but is susceptible of various other changes and modifications without departing from the spirit thereof.

What is claimed is:

1. In an ice maker, an ice mold, means for removing the frozen contents from said mold, a thermal motor for driving said removing means, means for refrigerating said ice mold and said thermal motor, and means actuated by said thermal motor upon being refrigerated to a predetermined temperature for energizing said thermal motor.

2. In an ice maker, an ice mold, means for filling said mold with water to be frozen, means including a thermal motor for removing the frozen contents from said mold, means for refrigerating said ice mold and said thermal motor, means for heating said thermal motor, and means responsive to said thermal motor being refrigerated to a predetermined temperature for energizing said heating means.

3. In an ice maker, an ice mold, means for removing the frozen contents from said mold, a thermal motor adapted upon being heated from a first predetermined temperature to a second predetermined temperature to drive said removing means to effect removal of the contents of said mold, means for refrigerating said mold and said thermal motor, means for heating said thermal motor, and means responsive to said thermal motor being cooled to a said first temperature for energizing said heating means.

4. In an ice maker, an ice mold, means for filling said mold with water to be frozen, means for removing the frozen contents from said mold, a thermal motor adapted upon being heated from a first predetermined temperature to a second predetermined temperature to drive said removing means to effect removal of the contents of said mold, means for refrigerating said mold and said thermal motor, means for heating said thermal motor, means responsive to said thermal motor being cooled to its said first temperature for energizing said heating means, and means responsive to said thermal motor being heated to its said second temperature for controlling said filling means.

5. In an ice maker, an ice mold, means for removing the frozen contents from said mold, a thermal motor including a member adapted to occupy one position when said motor is at a first predetermined temperature, and movable to a second position when said motor is heated to a second predetermined temperature higher than said first temperature, means for transmitting movement of said member to said removing means, means for refrigerating said mold and said motor whereby said mold and said motor are cooled at analogous rates, means for heating said thermal motor, and means responsive to movement of said member to its first position for rendering said heating means operative.

6. In an ice maker, an ice mold, means for filling said ice mold with water to be frozen, refrigerating means for said mold, means for removing ice from said mold, heat motor means for driving said ice removing means, said heat motor means including a member adapted to occupy a first position when said heat motor means is at a first predetermined temperature, and to move to a second position when said motor means is heated to a second predetermined temperature higher than said first temperature, said heat motor means being subjected to the effect of said refrigerating means, whereby said ice mold and said heat motor means are cooled at analogous rates, means for heating said heat motor to cause said member to move from its first position to its second position, means connecting said member to said ice removing means whereby movement of said member from its first to its second position causes ice to be removed from said mold, and means responsive to movement of said member from its second position to its first position for rendering said heating means operative.

7. In an ice maker, an ice mold, means for removing the frozen contents from said mold, a container, an expansible-contractible material in said container adapted

to undergo substantial volumetric change when subjected to a change in temperature between two predetermined values, a movable member associated with said container and actuated between two positions by the expansion and contraction of said material, means for transmitting movement of said member to said removing means, means for refrigerating said mold and said container whereby said mold and said container are cooled at analogous rates, means for heating said container, and means responsive to movement of said member for controlling said heating means.

8. A self controlling power unit for ice makers or the like comprising, a container, a substance in said container, said substance being adapted to undergo substantial volumetric change when subjected to a change in temperature between two predetermined values, a movable member associated with said container and actuated by said substance when said substance undergoes volumetric change, whereby said member occupies one position when said substance is at the lower of its said two temperature values and another position when said substance is at the higher of its said temperature values, movement of said member being employed to actuate an ice making mechanism, means for heating said substance, and means responsive to said substance being cooled to the lower of its said two temperature values for rendering said heating means operative.

9. In an ice maker, an ice mold, means for removing the frozen contents from said mold, a thermal motor for driving said removing means, said thermal motor comprising a container, an expansible-contractible material in said container adapted to undergo substantial volumetric change when subjected to a change in temperature between two predetermined values, a movable member associated with said container and actuated between two positions by the expansion and contraction of said material, means for transmitting movement of said member to said removing means, a heat storage mass in heat exchange relationship with said container for increasing the heat storage capacity of said thermal motor, means for refrigerating said mold and said motor, whereby said mold and said motor are cooled at analogous rates, means for heating said thermal motor, and means responsive to movement of said member for controlling said heating means.

10. In an ice maker adapted for use in a domestic refrigerator or the like having refrigerating means, an ice mold, means for removing the frozen contents from said mold, said removing means including a thermal motor and means for heating said thermal motor, said ice mold and said thermal motor both being adapted to be subjected to the effect of said refrigerating means, and means responsive to said thermal motor being refrigerated to a predetermined temperature for energizing said removing means.

11. In an ice maker adapted for use in a domestic refrigerator or the like having refrigerating means, an ice mold, a thermal motor for removing ice from said mold, means for heating said thermal motor to a first predetermined temperature, said thermal motor and said ice mold both being adapted to be subjected to the effect of said refrigerating means, and means responsive to said thermal motor being refrigerated to a second predetermined temperature lower than said first temperature for energizing said heating means.

12. In an ice maker adapted for use in a domestic refrigerator or the like having refrigerating means, an ice mold, means including a thermal motor and adapted upon heating of said motor to effect removal of ice from said mold, said ice mold and said thermal motor both being adapted to be subjected to the effect of said refrigerating means, means for heating said thermal motor, and switching means actuated by said thermal motor for controlling energization of said heating means.

13. In an ice maker adapted for use in a domestic

refrigerator or the like having refrigerating means, an ice making mechanism including an ice mold, a thermal motor adapted upon being heated to actuate said mechanism, said ice mold and said thermal motor both being adapted to be subjected to the effect of said refrigerating means, means for heating said thermal motor, and switching means actuated by said thermal motor for controlling energization of said heating means.

14. A self-controlling power unit for ice makers or the like comprising, a container, a substance in said container, said substance being adapted to undergo substantial volumetric change when subjected to a change in temperature between two predetermined values, a movable member associated with said container and actuated by said substance when said substance undergoes volumetric change, whereby said member occupies one position when said substance is at the lower of its said two temperature values and another position when said substance is at the higher of its said temperature values,

10

15

movement of said member being employed to actuate an ice making mechanism, means for heating said substance, and switching means actuated by said member for energizing said heating means when said substance is cooled to said lower temperature value and for deenergizing said heating means when said substance is heated to said higher temperature value.
